Fixture Hanger for T-Bar Ceilings

Gary C. Scully, 351 Scenic Drive,
La Honda, Calif. 94020

Filed July 27, 1970, Ser. No. 24,133

Term of patent 14 years

Int. Cl. D26—99

U.S. Cl. D48—4

Fig. 2

Fig. 1

Fig. 3

Fig. 4

Fig. 5

Fig. 6

FIG. 1 is a side elevational view of a fixture hanger for T-bar ceilings showing my new design.

FIG. 2 is a top plan view thereof.

FIG. 3 is a bottom plan view thereof.

FIG. 4 is an enlarged cross-sectional view taken on line 4-4 of FIG. 1.

FIG. 5 is an enlarged end elevational view taken on line 5-5 of FIG. 1.

FIG. 6 is a perspective view thereof, the T-bar ceiling and the electrical fixture being shown in broken lines for illustrative purposes only.

I claim:

The ornamental design for fixture hanger for T-bar ceilings, as shown and described.
